DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

SUPERSENSITIZED SILVER HALIDE PHOTOGRAPHIC EMULSIONS

Cynthia G. Ulbing, Fairport, and Mary Jane W. Brizee, Pittsford, N.Y. (both of Kodak Park, Rochester, N.Y. 14650)

Filed Dec. 12, 1969, Ser. No. 884,705

Int. Cl. G03c 1/28

U.S. Cl. 96—104

No Drawing 19 Pages Specification

Photographic silver halide emulsions are spectrally sensitized with a dye combination comprising (1) a benzimidazolonephthiocarbocyanine dye and (2) a benzimidazoloindocarbocyanine dye. A preferred combination comprises (1) a 4',5'-benzobenzimidazolothiocarbocyanine dye having the formula:

$X_1^\ominus$

and (2) a benzimidazoloindocarbocyanine dye having the formula:

$X_2^\ominus$

wherein n , k and p each represents a positive integer of from 1 to 2; m represents a positive integer of from 1 to 4; L_1 , L_2 and L_3 each represents a methine linkage; R_1 , R_2 , R_3 and R_4 each represents an alkyl group; R_5 , R_6 , R_7 and R_8 each represents an unsubstituted lower alkyl group; R_9 , R_{10} , R_{11} , R_{12} , R_{13} and R_{14} each represents a member selected from the group consisting of a hydrogen atom and a halogen atom; X_1 and X_2 each represents an acid anion; V represents a member selected from the group consisting of a hydrogen atom, a halogen atom, an alkyl group, an alkoxy group and an aryl group; W and Y each represents a member selected from the group consisting of a hydrogen atom, a halogen atom, a cyano group, an alkyl group, an alkoxy group, an acyl group of a monobasic fatty acid, an alkylaminocarbonyl group, a trifluoroalkyl group and a trifluoroalkylsulfonyl group; and Z represents a member selected from the group consisting of a hydrogen atom, a halogen atom, a sulfo group, an alkyl group, an alkoxy group and an aryl group. A typical example comprises a gelatin silver bromoiodide emulsion containing the dye combination of (1) anhydro-5,6-dichloro-1-ethyl-3-(3-sulfobutyl)-3'-(3-sulfopropyl)-4',5'-benzobenzimidazolothiocarbocyanine hydroxide and (2) anhydro-5,6-dichloro-1-ethyl-1',3',3'-trimethyl-3-(4-sulfobutyl)benzimidazoloindocarbocyanine hydroxide.
